UNITED STATES PATENT OFFICE.

ISIDOR KITSEE, OF PHILADELPHIA, PENNSYLVANIA.

TELEPHONE SYSTEM.

SPECIFICATION forming part of Letters Patent No. 785,673, dated March 21, 1905.

Application filed February 24, 1902. Serial No. 95,281.

To all whom it may concern:

Be it known that I, ISIDOR KITSEE, of the city and county of Philadelphia, State of Pennsylvania, have invented certain new and useful Improvements in Telephone Systems, of which the following is a specification.

My invention relates to improvements in telephone systems, and has more special reference to systems wherein two or more outlying subscribers' circuits are centered in one exchange and are provided therein with a common source of electric energy.

As much as the systems of to-day are improved their arrangements are still subject to manifold disadvantages, and it is the aim of my invention to overcome these disadvantages and to produce a system having improved features, as follows:

First, secrecy. In the central arrangement of to-day the operator can listen to the conversation of two subscribers connected for the purpose of intercommunication at any time she may desire. To subscribers this fact is a great annoyance and I therefore have eliminated this objection, and my invention assures positive secrecy in so far that it makes it impossible for the operator to "break in" on lines connected for intercommunication.

Second, assurance of calling. To-day the subscriber calling has no means of ascertaining if the operator at the exchange has called or, as the technical term is, has "rung up" the second subscriber, and this uncertainty often makes the subscriber calling impatient and unjust. With the system as later on to be described the "ringing up" of the subscriber called is automatically brought to the notice of the subscriber calling.

Third. To-day the operator has it in her power to ring up the subscriber called for such length of time as she desires. In my system the time of the ringing up lays entirely with the subscriber calling, and he does not need to depend in this respect upon the operator.

Fourth. With the systems of to-day disputes often arise between the subscriber and central on account of the number of calls and the time for each call. With my system the calls

are automatically registered through the action of the subscriber himself.

Fifth. To-day from five to seven distinct operations are necessary to connect two subscribers—closing the listening-key, making "busy" test, inserting plug in jack of calling-line, releasing listening-key, closing ringing-key, releasing ringing-key, and inserting plug in jack of circuit to be called—and if the subscriber called does not answer at once the operation with the ringing-key has to be repeated.

As soon as the supervisory lamps show that both subscribers have finished conversation then the two plugs of the subscribers have to be removed from the switchboard, or, as it is technically called, the switchboard has to be "cleared" of the two plugs. In my system it is only necessary for the operator as soon as she sees her plug-lamp light to place the plug at a designated point on her desk and then after ascertaining the wishes of the subscriber to place this plug in contact with the jack of the subscriber to be called. All other operations are automatically performed.

It is readily seen that with this system an operator may be enabled to attend to double the number of subscribers' circuits as with the systems now in use.

From the description and drawings it will also be seen that in my system the wiring is far less complicated than in the systems to-day in use and contains a lesser number of devices, and therefore the liability of disorder is greatly lessened.

Referring now to the drawings, in which similar characters indicate similar parts, Figure 1 is a front elevation of one of the operators' switchboards and desks. Fig. 2 is a vertical section through one of the operators' switchboards, showing the same in use from either side. Fig. 3 is a plan view of one of the jacks in one of the switchboards with the upper shell removed, showing the parts in their normal positions. Fig. 4 is a similar view to Fig. 3, only showing a plug inserted in one end. Fig. 5 is a transverse section through one of the jacks. Fig. 6 is a vertical longitudinal section through one of the jacks. Fig. 7 is a longi-

tudinal section through one of the plugs. Fig. 8 is a diagram of the telephone-exchange. Fig. 9 is a diagram illustrating three subscribers' stations and their connections at the exchange. Fig. 10 is a diagram showing one subscriber's station and its connection in the exchange.

a represents the receiver-lever within the subscriber's station.

10 *b* is a contact-point electrically connected with the ground *c*.

d is a contact-point electrically connected to one terminal of the primary *f* of an inductorium.

15 *g* is the secondary of the inductorium, in which the receiver *z* is placed.

h is the transmitter, and *j* is the bell.

1 and 3 are the main wires leading from the subscriber's station to the exchange.

20 *k* is a common battery to which the wire 3 leads.

l is an electromagnet placed in series in the wire 3.

25 *m* is a contact-point; *n*, the armature of the electromagnet *l*.

q is the electric-light board, which has the openings formed through the same, in which openings are placed electric lights *s*, which lights are in a circuit formed by wires leading from the contact *m*, through a common battery *p*, through the light, and back to the armature *n*.

A is one of the operators' switchboards and desk.

35 B represents the switchboard, and C a desk upon each side of the same.

D represents the jacks in the switchboard, each of which jacks is composed of a soft-iron core *D'*, which passes longitudinally through the same, and the rod *D*², which normally projects a slight distance from the core *D'*. The central portion of the core *D'* is cut away, so as to expose the rod *D*², and extending from this rod in the center is the pin *D*³, which normally lies in contact with a plate *D*⁴, insulated from the plug *D'*.

40 *D*⁵ is a pin extending upward from the rod *D*² in the center, and *D*⁶ represents springs connected to the pin and extending out from each side of the same and secured to the plug at each end for the purpose of holding the rod *D*² in the center.

*D*⁷ is a semicircular shell secured below the plug *D'* and insulated therefrom.

55 *D*⁸ is a semicircular shield arranged above the core *D'* and insulated therefrom.

E is one of the plugs which consists of the electromagnet *E'*, provided with the soft-iron core *e*, which has the two soft-iron face-plates *e'* and *e*² and the soft-iron shell *E*² in magnetic contact with the face-plates *e*² for the purpose of concentrating the lines of force at that end which is provided with the face-plate *e'*. Around this core is wound the coil *e*³. This

65 plug also consists of the outer conducting-shell *E*³, insulated from the magnetic shell *E*².

F is an induction-coil composed of the primary coil *F'* and the secondary *F*².

*F*³ is a soft-iron core around which the two coils are wound.

70 *F*⁴ is a pivoted armature adapted to be attracted by the core *F*³ when energized, and *F*⁵ is a contact-point with which the armature *F*⁴ is adapted to make contact. At the opposite end of the core is arranged a pivoted armature *F*⁶, which is adapted to make contact with the point *F*⁷ when attracted by the core.

75 G is a second induction-coil, of which *G*² is the primary and *G*³ the secondary.

*G*³ is the core around which the primary and secondary are wound.

80 *G*⁴ is a pivoted armature adapted to be normally in contact with the point *G*⁵, but to be pulled away from the same when the core *G*³ is energized.

85 *G*⁶ is a pivoted armature arranged at the opposite end of the core *G*³, and when said core is energized said armature is adapted to make contact with the point *G*⁷.

C represents openings formed through the operators' desks *C*, and underneath these openings are arranged the springs *I*, which make contact with the contacts *J* when the plugs *E* are removed from said openings, as will hereinafter appear.

90 H is a battery included in the wire leading from spring *I* to the contact *F*⁷.

K is the desk electric light.

95 L is an electromagnet, and O is a battery, both of which are included in the circuit extending from contact *G*⁷ to armature *G*⁶.

M is an armature adapted to be attracted by the magnet *L*, and N is a step-by-step indicating device adapted to be actuated by armature *M*.

100 P is an electromagneto-ringing device, and Q is the ground with which it is connected.

R is the socket in which the plugs are placed to connect any one of the lines with the operator's phone. This socket consists of the metallic shell *R'*, which is adapted to make contact with the shell *E*³ of the plug, and inside of the shell *R'* and insulated therefrom is the metallic plug *S*, which is adapted to make contact with the core of the plug.

110 T is the operator's receiver, *T'* the transmitter, and *T*² is the inductorium of the operator's telephone, and *T*³ is the operator's battery.

120 I will first describe the connection and wiring at the subscriber's station, as is more fully illustrated in Fig. 10. I have in my arrangement, as illustrated, omitted the branch circuit containing the alarm and the condenser as usually employed in the systems of to-day, 125 and I leave one line of the metallic circuit normally disconnected in its entirety from the hook-lever manipulated through the remov-

ing of the receiver, and I not only connect normally the second line to this hook-lever, but bring the hook-lever normally in contact with a grounded alarm. This arrangement 5 has the advantage that the condenser can be entirely omitted, and it also has the advantage that the comparatively dear alarm-bell of to-day can be replaced by a comparatively cheap alarm-bell to be used with the interrupted current. In fact, I prefer to use a highly-inductive contrivance—one which retards greatly the flow of induced currents, so as to retard as much as possible the flow of earth-currents through that branch of the circuit which is normally 10 connected through the lever with the ground. In the case where the polarized bell of to-day is replaced by a device such as described the source of electricity P, which is grounded at Q, can then be either a direct and straight or 15 interrupted current; but, if it is desired, this part of my invention may be omitted and the bridge as usually employed may be replaced.

The drawing Fig. 10 clearly illustrates the circuit, consisting of wires 1 and 3, as normally broken, because the wire 3 normally disconnects from the wire 1 and only connects therewith through the lever *a* when the receiver *z* is removed, and this lever comes in contact then with the contact *d*, which is the 20 terminal of the line-wire 3. This line-wire contains in series the transmitter *h* and the primary *f* of the inductorium, the secondary *g* of which is connected to the receiver *z*. The wires 1 and 3 form the circuit of the subscriber centered in the exchange, and the wire 3 is therein connected to the common battery *k*.

A feature distinguishing this invention from the systems of to-day consists in the employment 25 of a light-board and in the position of the same relative to the different switchboards and operators attending thereto.

I omit entirely the supervisory lamps of the present systems and substitute therefor the light-board, wherein each subscriber's circuit is provided with an annunciator, preferably in the shape of an electric lamp, and this lamp-circuit is preferably placed in a local circuit adapted to be operated by a relay placed in series 30 in the subscriber's circuit. The light-board is placed at right angles to the switchboards, so that the operators attending to said switchboards can, through a slight movement of the head, readily ascertain which of the 35 lights on this light-board are lighted. The light-board presents for this purpose a double front—that is, the lights in this board can be distinguished from both sides, (front as well as rear,) as is clearly illustrated in Fig. 8, in 40 which *q* represents the light-board, *r* the openings, and *s* the electric lights in same, and in which *A* represents the different switchboards, and *X* the positions of the different operators attending to said switchboards. The function of this light-board is

to notify, through the state of the different lamps it contains, the status of the different circuits connected thereto, if said circuits are busy or if said circuits are idle. The lighting of a lamp indicates that the circuit connected thereto is employed and can therefore not be used by any of the operators for the purpose of connecting the same to a calling-subscriber. The light-board therefore takes the place of the so-called "testing" of 70 to-day and makes unnecessary that operation of the operator which to-day pertains to the testing of the line. The operator having a call for a certain line looks up to the light-board and ascertains if the circuit of the 75 called-for subscriber is busy or not. If the lamp designating the number of the desired subscriber is not lighted, the circuit is not busy and the connection can be made. If, on the contrary, the lamp designating his number is 80 lighted, then the circuit is busy and the connection cannot be made.

Each lamp carries on each side the number of its subscriber, and the opening may also be provided, if necessary, with a magnifying-glass, and it is obvious that with such arrangement the operator can easily ascertain by a mere look at the board if the number desired by her is busy or not.

The present invention also consists therein 95 that each subscriber's circuit has connected thereto in series, at the desk of the operator in charge of said circuit, the primary of an inductorium, the secondary of which is in inductive relation to the plug-cord, with which 100 each of said circuits is provided.

In the experiments carried out for the purpose of ascertaining the necessary resistance and inductive values between primaries and secondaries I found that it would be impractical to give the secondary a high-resistance value if this secondary should be connected through the plug to the circuit called, an operation which will later on be more fully described, and as a result of these experiments 105 I prefer the arrangement as illustrated in Fig. 10, in which the primary of the inductorium connected in series to the subscriber's circuit is provided with a secondary of high inductive value and wherein this secondary 110 is connected in series with a high inductive secondary of a second inductorium, the low-resistance primary of which is connected to a plug-circuit. In other words, I make use of two induction coils or transformers, the first 115 induction-coil being in reality a step-up and the second induction-coil being in reality a step-down transformer. In Fig. 10 this arrangement is illustrated as to consist of the step-up transformer consisting of the core 120 F¹, the primary F¹, and the secondary F², and the step-down transformer consisting of the core G¹, the secondary G², and the primary G¹. The primary F¹ of the first or step-up transformer is connected in series to the cir- 125 130

cuit 1 3, and the secondary F^2 of this transformer is connected in series to the secondary G' of the second or step-down transformer, the primary of which is connected to the plug-circuit.

A further feature of this my invention consists therein that the plug constitutes an electromagnet and two conducting parts insulated from each other, each part connected to one contact of the plug-circuit forming the terminals of the primary G^2 . This plug E , as illustrated in Fig. 7, includes the electromagnet E' , consisting of the soft-iron core e , provided with the two soft-iron face-plates e' and e^2 and the soft-iron shell E^2 in magnetic contact with the face-plates e' for the purpose of concentrating the lines of force at that end which is provided with the end plate e' . Around this core is wound the coil e^3 . The plug E also consists of the outer conducting-shell E^3 , insulated from the magnetic shell E^2 . To this outer shell is connected, as said above, through the cord, one terminal of the primary G^2 , the other terminal of which is connected to the face-plate e' or its equivalent, the face-plate e^2 , in electrical contact with the face-plate e' through the core e .

The present invention also contemplates an arrangement whereby the ringing-circuit is automatically connected to the circuit called through the insertion of the plug. This arrangement is clearly illustrated in Fig. 10. P designates the source of ringing-current, which is grounded with one terminal at Q . A branch at the other terminal connects with a contact-point F^5 in proximity to the armature F^4 of the core F^3 of the inductorium F . This armature is in electrical contact with the armature G^4 of the inductorium G , and in proximity to this armature is the contact G^5 , connected through the plug-circuit with the outer shell E^3 of the plug E . Normally—that is, when the circuit to which the inductorium F belongs is idle—the armature F^4 is drawn by its spring out of connection with the contact F^5 ; but the armature G^4 is normally connecting with the contact G^5 . Should now the subscriber of the circuit consisting of the wires 1 and 3 remove his receiver from the hook, thereby closing the circuit, then the core F^3 will be energized, the armature F^4 will be drawn toward that core and in contact with the point F^5 , closing the circuit consisting of ground Q , source of current P , contact F^5 , armature F^4 , armature G^4 , contact G^5 , and shell E^3 of the plug E , and if, as will later on be more fully described, the shell E^3 connects through the insertion of the plug with the grounded circuit-wire of the subscriber called then it is obvious that the generated current in P will find a path through the circuit just described and the grounded circuit-wire of the subscriber called.

In the general description, later on to be given, I will set forth the manner in which

the ringing-circuit is broken as soon as the subscriber called has taken his receiver from the hook.

A further provision of the present invention consists therein that the calls are automatically registered. This arrangement is illustrated in Fig. 10 and consists of electromagnet L , provided with the armature M and ratchet-wheel N in proximity to that part of the armature adapted to move this ratchet-wheel one or more points, as desired, through the energizing of the core of the electromagnet L . The coil of this electromagnet is connected to the circuit consisting of the battery O , armature G^6 , and contact-point G^7 of the inductorium G . Normally this circuit is open, for the reason that the armature is drawn from its contact G^7 by its spring; but when through the insertion of the plug (as will later on be fully described) the same connects with the circuit called and the subscriber of this circuit answers by removing his receiver. Then the core of the inductorium G will be energized and the armature G^6 will be drawn upward and in connection with the contact G^7 closing the circuit containing the electromagnet L , whereby the armature will be drawn toward its core and will manipulate the ratchet-wheel. This ratchet-wheel connects with any of the well-known registering devices, and as it is the practice to illustrate a registering device by showing only the mechanism actuating the same and the ratchet-wheel I do not deem it necessary to illustrate in the drawings or describe in the specification a complete registering device, as the construction of such devices does not form the subject-matter of this my invention and is well understood by persons versed in the art.

I will now describe the switchboard. Both sides of the same can be used in the connection of subscribers, and therefore each is provided with the necessary operator's desk, as is well illustrated in Fig. 2, wherein an operator is stationed on each side of the board. In this figure the center partition of the switchboard is designated by the letter B' , and this center board is adapted to carry the different circuits designed to be connected to the different jacks. To this center board are also secured the spring-jacks D , with their shields D^8 , preferably in the shape of a semicircle, as illustrated. The center board is closed on each side with an end board, (designated in the drawings by the letter B^2 .)

A further feature of the present invention is the construction of the spring-jack. This spring-jack embraces the following parts, (illustrated in detail in Figs. 3, 4, 5, and 6:) the core of soft iron D' , provided with the movable pin D^2 , longitudinally centered through the two springs D^6 , connected to the pin-head D^5 . This movable pin is provided with the contact D^3 , normally in contact with the contact-plate D^4 , secured to but insulated from

the soft-iron core. The spring-jack consists also of the semicircular conducting-piece D^3 in proximity to but insulated from said core. The contact-plate D^4 is provided with means 5 to connect thereto one line of the subscriber's circuit, and the soft-iron core is provided with means to connect thereto the other line of said circuit. The second line of the circuit is connected to the semicircular shell D^7 . As 10 long as the contact D^3 connects with the contact-plate D^4 that part of the circuit centered in the exchange is unbroken; but as soon as through the insertion of the plug E the pin D^2 is pushed inward, breaking the contact between 15 D^3 and D^4 , the circuit is broken and the plug-circuit may be made part of the subscriber's circuit.

My invention therefore consists of the features and arrangements heretofore mentioned 20 and hereinafter to be described, and particularly pointed out in the claims following this specification.

I will now describe the *modus operandi* of my invention, taking for granted that the subscriber's station is provided with an arrangement, as illustrated more specially in Figs. 9 and 10. I have in these figures, as was clearly stated in the description of the drawings, omitted the permanent connection of one of the 25 circuit-wires through a condenser and alarm device with the lever a , and I have connected this lever with the interposition of an alarm device to the ground C ; but it is obvious that the usual arrangement may be used and the 30 ground entirely dispensed with. Normally—that is, when the circuits are idle—the flow of the battery k is interrupted because one of the line-wires—in the drawings the line-wire 3—is out of electrical contact with the second line-wire—in the drawings the line-wire 1—and with the exception of this break the circuit is 35 a continuous one, as follows: commencing at the break in the subscriber's station, as in Fig. 10, contact d , primary of inductorium f , transmitter h , wire 3, common battery k , coil of 40 electromagnet l , soft-iron core D' , movable pin D^2 , contact D^3 , contact-plate D^4 , of the spring-jack of the first switchboard, passing then to the spring-jack of the second switchboard if more than one switchboard is in the 45 circuit, where the connection is the same as in the spring-jack just described, and from the contact-plate D^4 of the spring-jack of the last switchboard to one terminal of the primary F' of the inductorium F , the other terminal of 50 which is connected to the semicircular shell D^7 of the spring-jack of the last switchboard, and connects then to the semicircular shell of the spring-jack of the switchboard preceding, till 55 the semicircular shell of the spring-jack of the first switchboard is reached, where the same connects with the second line-wire—in the drawings the line-wire 1—connected at the subscriber's station to the lever a in electrical 60 connection through contact b and alarm j with

the ground c . It is now supposed that the subscriber No. 1 wishes to communicate with the exchange. He removes, as usual, the receiver z from the hook a , thereby bringing this lever or hook in contact with the point d . This 70 closes the subscriber's circuit, and the current-flow of the battery k has a continuous path, as is illustrated in Fig. 10, from the positive pole of said battery through wire 3, transmitter h , primary of inductorium f , contact d , lever a , 75 line-wire 1, through the shells D' of the different spring-jacks of the different switchboards, the primary F' of the inductorium F , the different spring-jacks, the coil of electromagnet L , back to the negative pole of said battery. 80 In Fig. 9 the coils of electromagnets l are placed in the line 1 instead of the line 3, as is illustrated in Fig. 10. This difference of placement does not alter the principle or working of the arrangement and only illustrates 85 the flexibility of the system described. As soon as the contact between d and a at the subscriber's station is established the electromagnet l is energized through the flow of the current, and in consequence the armature n 90 is brought in contact with the point m , thereby closing the local circuit containing the battery p and the lamp s of the light-board q . At the same time the core F^3 of the inductorium F will also be energized, and in consequence 95 thereof the armature F^6 will be brought in contact with the point F^7 , thereby closing the circuit containing the battery H , the operator's lamp K , with its shunt I , and the coil e^3 100 of the plug E ; but at the same time the armature F^4 will be drawn in contact with the point F^5 , which point is in contact with one terminal of the ringing-generator P . The lighting of the two lamps s in the light-board and K at the operator's desk will at one and the same 105 time first notify every operator in the room that the particular circuit is busy and, second, notify the operator having charge of this circuit that the same is calling, and the current-flow through the coil e^3 will energize 110 the core e of the plug E . The operator being aware through the lighting of the lamp that the subscriber is calling removes the plug E of this particular circuit from the opening, in which it is held normally in an upright position, and places it face downward in the listening-jack R , as is clearly illustrated in Fig. 2 by the left-hand operator and as is also illustrated in Fig. 9, wherin the circuit No. 3 is 115 illustrated as in the act of calling and wherin the plug of said circuit is placed in the operator's listening-jack. The removing of the plug from its place allows the spring shunt-arm I to connect with the contact J , thereby shunting the lamp K and extinguishing the 120 same. When the lamp K is shunted, the circuit will be from the battery H to the contact F^7 , armature F^6 , coil E' of the plug E , contact J , arm I , and back to the battery H . The operator ascertains now the circuit number 130

desired and having ascertained this number looks at the light-board to find out if the same is busy or not, and if the desired number is idle she inserts the plug E in the spring-jack denoting this circuit, as is clearly illustrated by the right-hand operator in Fig. 2 and in Fig. 9, wherein subscriber No. 1 is illustrated as called up and wherein the plug of circuit No. 2 is placed in the jack of circuit 10 No. 1, thus indicating that circuit No. 2 was calling for circuit No. 1. It was clearly set forth in the description of the drawings that the plug consists in part of an electromagnet, and the insertion of the plug will therefore result therein that the same is drawn tightly at the face-plate of the jack in which it is inserted and will through this operation uncenter the pin D², thereby breaking the contact between it and the contact-plate D¹. 15 At the same time it will connect that part of the circuit called connected to the semicircular shield D⁷ of the jack through the plug-shell E³ with one terminal of the primary G² of the plug-inductorium G and will connect that 20 part of the circuit called which is connected to the soft-iron core of the jack through the contact of the same with the core of the plug with the other terminal of said primary. The circuit called therefore will, as in Fig. 9, consist 25 of the ground c, the alarm j, contact b, lever a, wire 1, coil of electromagnet l, semicircular shell D⁷, plug-shell E³, that wire of the plug-cord connected to said shell and contact G⁵, respectively, contact G⁶, armature G⁴, 30 armature F⁴, contact F⁵, ringing source P, and ground Q. As long as the subscriber called does not answer by removing his receiver that part of his circuit consisting of point d, primary f of receiver, transmitter h, wire 3, and 35 battery k is cut out and his alarm or other annunciator j is actuated by the ringing-current. Should the subscriber called answer by removing his receiver from the hook, then this hook will contact with the point d, breaking 40 the contact with the grounded circuit containing the alarm. This alarm will therefore cease to ring and the following circuit will be established: lever a, wire 1, coil of electromagnet l, shell D⁷ of spring-jack, shell E³ 45 of the plug, primary G² of inductorium G, core e of the plug, soft-iron core D¹ of spring-jack, battery k, wire 3, transmitter h, primary f, and contact d. Through the flow of this 50 current the core of the electromagnet l will be energized, the armature n will contact with the point m, and the lamp s of the light-board q will light. So, also, will the core G² of the inductorium G be energized, drawing away from its contact G⁵ the armature G⁴, thereby 55 breaking the electrical connection with the circuit containing the ringing alarm. Through this 60 operation all the connections of the circuits between it and the ground are broken. At the same time the armature G⁶ will be drawn 65 in contact with the point G⁷ and the circuit

containing the battery O and electromagnet L will be established, operating the armature M and through it the ratchet N, which ratchet operates the meter device. The communication between the circuit called and the circuit 70 calling is now established through the inductoriums F and G.

In the switchboard with which I experimented I used seven cells for the energizing of the plug, and I found that the contact between the plug and the jack-core was firmly enough established not to be broken through the falling of the other plugs. 75

I have carried on communication between two circuits through substantially the arrangement as illustrated in the drawings and described above, and I have found that this arrangement is even to be preferred to the arrangement as now practiced, wherein the two circuits communicating are connected in series with each other and wherein the current of the common battery flows to both circuits in series. One of the reasons for preferring this arrangement is that the high potentials due to the inductive action in the secondary 80 are better transmitted over the wires of the second circuit than the slight variations of the primary current due to the varying resistance of the transmitter. These experiments were carried out with the help of two assistants, and the correctness of each of the arrangements was thereby established. 90

As long as communication lasts the plug will remain in connection with the spring-jack, and to guard the same more efficiently 100 against other dropping plugs the upper part of the jack is provided with a semicircular shield D⁸. When the party calling replaces his receiver on its hook, then the electromagnet l and the core of the inductorium f and 105 the core of the plug E will be demagnetized. The plug will break its connection with the spring-jack and will, guided by the weight with which the plug-circuit is usually provided, return to its normal place, and the 110 lamps of the light-board will be extinguished; but the lamp of the circuit called will be lighted till the party called has also replaced his receiver.

Such in broad outlines are the arrangements 115 and devices for the system embodying my invention. It is believed that with these arrangements all possible exigencies are met, and should the exchange provided with this system also be provided with so-called "trunk-lines" connecting one exchange to the other 120 then it is best that the circuit of these trunk-lines should be a normally closed one.

I have enumerated different novel devices and arrangements embodied in my invention. 125 At a first glance it may seem that these devices and arrangements are entirely apart and independent of each other, yet to persons versed in telephone-exchange work it will be quite apparent that the system as such to be 130

efficient and complete has to embody every one of the features enumerated, and the entire structure represents one undivided system improved at different points, the various devices and arrangements being interdependent upon each other.

Having now described my invention, what I claim as new, and desire to secure by Letters Patent, is—

- 10 1. In a telephone system wherein two or more outlying circuits center in one exchange, a switchboard, an operator's desk for said switchboard, an inductorium at said desk for each of the circuits in the charge of the operator at said desk, the coils of which inductorium are conductively independent, one of the coils of each inductorium being at all times electrically connected to its outlying circuit, and a connecting - plug also at said desk for each of said circuits and in inductive relation to said coil.
- 15 2. In a telephone system wherein two or more outlying circuits center in one exchange, a switchboard, an operator's desk for said switchboard, an annuating-lamp for each of the circuits in the charge of the operator at said desk, a shunt-circuit related to each of said lamps, means for lighting said lamps through the closing of the circuits at the out- 20 lyng stations, and a connecting-plug for each of said circuits operatively related to the lamp thereof, said plugs being adapted to extinguish the lamps of the respective circuits by the removal of the plugs from their normal positions in the desk, whereby said shunt-circuits are established around said lamps.
- 25 3. In a telephone system wherein two or more outlying circuits center in one exchange, a switchboard, an operator's desk for said switchboard, an inductorium at said desk for each of the circuits in the charge of the operator at said desk, the primaries of said inductoriums being normally connected to their respective circuits, a second inductorium one 30 coil of which is connected to the secondary of the first-mentioned inductorium, and a plug connected to the terminals of the other coil of the second inductorium for connecting said terminals with a second outlying circuit.
- 35 4. In a telephone system wherein two or more outlying circuits center in one exchange, a switchboard, an operator's desk for said switchboard, an inductorium at said desk for each of the circuits in the charge of the operator at said desk, a circuit containing a source of current, an annuating-lamp, means influenced by said inductorium for closing said circuit, a plug, a seat therefor, and means for extinguishing the lamp by the removal of the 40 plug from its seat.

- 45 5. In a telephone system wherein two or more outlying circuits center in one exchange, a switchboard, an operator's desk for said switchboard, an inductorium at said desk for each of the circuits in the charge of the oper-

ator at said desk, a ringing-circuit, a signaling mechanism at a subscriber's station, and means influenced by said inductorium for closing said ringing-circuit to operate said signaling mechanism.

70

6. In a telephone system wherein two or more outlying circuits center in one exchange, a switchboard, an operator's desk for said switchboard, an inductorium at said desk for each of the circuits in the charge of the operator at said desk, a ringing-circuit, a circuit containing a source of current and an annuating-lamp, and means influenced by said inductorium for closing the ringing and lamp circuits.

75

7. In a telephone system wherein two or more outlying circuits center in one exchange, a switchboard, an operator's desk for said switchboard, an inductorium at said desk for each of the circuits in the charge of the operator at said desk, a second inductorium in inductive relation to the first-mentioned inductorium, a ringing-circuit, a plug for connecting said second inductorium with a second outlying circuit, and means influenced by said second inductorium for closing and opening the ringing-circuit through said plug.

80

8. In a telephone system wherein two or more outlying circuits center in one exchange, a switchboard, an operator's desk for said switchboard, an inductorium at said desk for each of the circuits in the charge of the operator at said desk, the primaries of said inductoriums being normally connected to their respective circuits, a second inductorium in inductive relation to the first-mentioned inductorium, and a plug connected to one of the coils of said second inductorium for connecting the latter with the outlying circuit.

90

9. In a telephone system wherein two or more outlying circuits center in one exchange, a switchboard, an operator's desk for said switchboard, a connecting-plug at said desk for each of the circuits in the charge of the operator at said desk, an electromagnet in the circuit of said connecting-plug, a pair of armatures for said electromagnet, a ringing-circuit in which one of said armatures is included, and by which said circuit is opened and closed, and a circuit including the other armature and in which are included means to record the fact that the circuit called has answered.

100

10. In a telephone system wherein two or more outlying circuits center in one exchange, a switchboard, an operator's desk for said switchboard, an inductorium at said desk for each of the circuits in the charge of the operator at said desk, and a connecting-plug also at said desk for each of said circuits, said plug having an electromagnet and means connected to the terminals of one coil of said inductorium for connecting the latter to the jack of a called circuit.

110

11. In a telephone system wherein two or more outlying circuits center in one exchange,

130

- 20 a switchboard, an operator's desk for said switchboard, electromagnetic means at said desk for each of said circuits, a plug having an electromagnet, a local circuit in which said 5 electromagnet is included, and means also included in said local circuit and adapted to be influenced by the electromagnetic means of the outlying circuits for closing said local circuit.
- 10 12. In a telephone system wherein two or more outlying circuits center in one exchange, a switchboard, an operator's desk for said switchboard, a connecting-plug for each of the circuits in the charge of the operator at said 15 desk, an electromagnet for each of said plugs, a local circuit including said electromagnet and an annunciating-lamp, and means also included in said local circuit and influenced by the outlying circuit for closing the local circuit.
- 20 13. In a telephone system wherein two or more outlying circuits center in one exchange, a switchboard, a series of jacks for said switchboard each of which is provided with a soft- 25 iron core, each of said outlying circuits being connected to one of said jacks and to a source of energy common to all of said circuits, an inductorium at said switchboard for each of said circuits, a plug at said switchboard for 30 each of said circuits the circuit of which is in inductive relation to one coil of the inductorium of that circuit, and electromagnetic means carried by each of said plugs and adapted to be attracted by the soft-iron core of the jacks 35 in which said plugs are inserted.
14. In a telephone system, a series of incoming circuits connected to the switchboard, part 40 of said circuits being connected to one coil of an inductorium in inductive relation to a second inductorium, and a connecting-plug connected to one coil of said second inductorium and adapted to adhere to any of the jacks in the switchboard through electromagnetic action to thereby inductively connect 45 two of said incoming circuits.
15. In a telephone system wherein two or more outlying circuits center in one exchange, a switchboard for said exchange, a series of jacks for said switchboard, each jack connected 50 to the terminals of an outlying circuit, a series of plugs for said switchboard, each plug in inductive relation to one of the outlying circuits, an inductorium for each of said circuits, an annunciating-lamp for each of said 55 circuits, means in operative relation to said circuit to light said annunciating-lamp, and means in operative relation to the normal positions of said plugs to extinguish said annunciating-lamps.
- 60 16. In a telephone system wherein two or more outlying circuits center in one exchange, a switchboard, a series of jacks for said switchboard, each of said jacks connected to the terminals of one of the outlying circuits, a 65 series of plugs in inductive relation each to one of the outlying circuits, said plugs adapted to connect with the jacks of said switchboard and retain their position therein through electromagnetic action, a series of inductoriums one coil of each of which is connected 70 to one of the outlying circuits, means operatively connected to each of said circuits to annunciate the calling of said circuit, and means in operative relation to the normal position of the plug to terminate said annunciation.
17. In a telephone system embracing a series of outlying stations connected with their circuits to one central or exchange, a series 80 of switchboards located at said exchange, each of said switchboards provided with terminals connected to the incoming circuits, a jack for each of said circuits consisting essentially of a soft-iron core and movable means to change the electrical connection of the circuit to 85 which it pertains, a series of operators' desks each provided with a series of plugs connected each inductively to one of the incoming circuits, said plugs provided with electromagnetic means adapted to be energized when 90 placed in connection with one of the jacks on the switchboard and to remain energized throughout the period during which the circuit calling remains electrically closed, and an annunciating-lamp for each of said plugs, 95 said annunciating-lamp being in operative relation to the circuit to which said plug pertains and adapted to be made operative through the closing of said circuit and inoperative through the removing of the plug from its normal 100 position.
18. In a telephone system embracing a series of outlying stations connected with their circuits to one central or exchange, a series of switchboards located at said exchange, each 105 of said switchboards provided with terminals connected to the incoming circuits, a jack for each of said circuits consisting essentially of a soft-iron core and movable means to change the electrical connection of the circuit to 110 which it pertains, a series of operators' desks each provided with a series of plugs connected each inductively to one of the incoming circuits, said plugs provided with electromagnetic means adapted to be energized when 115 placed in connection with one of the jacks on the switchboard and to remain energized throughout the period during which the circuit calling remains electrically closed, an annunciating-lamp for each of said plugs, said 120 annunciating-lamp in operative relation to the circuit to which said plug pertains and adapted to be made operative through the closing of said circuit and made inoperative through the removing of the plug from its normal 125 position, and a light-board provided with a series of indicating-lamps, each lamp being in operative relation to one of the incoming circuits and adapted to remain operative as long as said circuit remains closed.

19. In a telephone system embracing an exchange wherein the circuits of a series of out-lying stations center, a source of electric current common to two or more of said electric circuits, jacks for said circuits adapted to change their electrical connection, means operatively related to each of said circuits to light two lamps, one located at a light-board, and one located at or near an operator's desk, a plug for each of said circuits, said plug inductively related to said circuit, and adapted to connect inductively said circuit with a second circuit, a ringing-circuit, means operatively related to said plug to connect said ringing-circuit to said second circuit, and means operatively related to said second circuit and plug-circuit respectively to disconnect automatically said ringing-circuit.
20. In a telephone system embracing an exchange wherein the circuits of a series of out-lying stations center, a source of electric current common to two or more of said electric circuits, jacks for said circuits adapted to change their electrical connection, means operatively related to each of said circuits to light two lamps, one located at a light-board, and one located at or near an operator's desk, a plug for each of said circuits, said plug inductively related to said circuit, and adapted to connect inductively said circuit with a second circuit, a ringing-circuit, means operatively related to said plug to connect said ringing-circuit to said second circuit, and means operatively related to said second circuit and plug-circuit respectively to disconnect automatically said ringing-circuit.
- 25
- 30

- 40

change their electrical connection, means operatively related to each of said circuits to light two lamps, one located at a light-board, and one located at or near an operator's desk, a plug for each of said circuits, said plug inductively related to said circuit, and adapted to connect inductively said circuit with a second circuit, a ringing-circuit, means operatively related to said plug to connect said ringing-circuit to said second circuit, means operatively related to said second circuit and said plug-circuit respectively to disconnect automatically said ringing-circuit, a call-registering device, and means operatively related to said second circuit to make operative said registering device to thereby indicate the successful call of the first-named circuit.

In testimony whereof I hereby sign my name, in the presence of two subscribing witnesses, this 21st day of February, 1902.

ISIDOR KITSEE.
